(57) **CLAIM**

The ornamental design for a decorative frame, as shown and described.

DESCRIPTION

FIG. 1 is a top, front, right side perspective view of a decorative frame, showing my new design;

FIG. 2 is a top, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a top plan view thereof;

FIG. 9 is an enlarged view of portion 9 in FIG. 2; and,

FIG. 10 is an enlarged view of portion 10 in FIG. 2.

The evenly dashed broken lines illustrate portions of the decorative frame and form no part of the claimed design.

The unevenly dashed broken lines define the boundaries of enlarged views and form no part of the claimed design.
